UNITED STATES PATENT OFFICE.

JOHN E. DOLDT, OF PORTLAND, MAINE, ASSIGNOR TO NATIONAL METAL SEAL CORPORATION, OF PORTLAND, MAINE, A CORPORATION OF MAINE.

CLOSURE FOR CONTAINING VESSELS.

1,300,252.

Specification of Letters Patent. Patented Apr. 15, 1919.

Application filed June 28, 1918. Serial No. 105,844.

To all whom it may concern:

Be it known that I, JOHN E. DOLDT, a citizen of the United States, residing at Portland, county of Cumberland, State of Maine, have invented certain new and useful Improvements in Closures for Containing Vessels, of which the following is a specification.

This invention relates to closures for containing vessels, and particularly to a closure for use with a vessel of the cam lug type. Such vessels usually have a series of four spaced lugs about their mouths and the closure consists of a rotatable cap having an equal number of inturned fingers adapted for camming engagement with said lugs. Where the container is of glass, considerable difficulty is met in molding the lugs uniformly and evenly so as to present to the fingers of the cap engaging surfaces disposed in the same horizontal plane. The tendency of the lugs to settle after molding often destroys the alinement, even when they have been accurately alined in the molding process. Inasmuch as these closures furthermore frequently are employed to seal vessels containing substances of a highly volatile nature, any variation between the lugs detracts from the tightness of the seal. Even where one lug is out of line only the thousandth part of an inch, the engagement of the cap at this point is correspondingly loose, and this variation is sufficiently serious to destroy the desired hermetic nature of the seal, permitting some of the contents of the vessel to escape.

I have discovered that by arranging the lugs at three equidistantly spaced points about the vessel mouth and radially with relation to the center of the pouring opening thereof they will always be alinable with reference to a cap of slightly larger diameter so that the engaging surfaces of all will be uniformly disposed in the annular path of rotation of the cap fingers, thus eliminating any tendency toward looseness and providing a hermetic seal of uniform tightness throughout the sealing area. My construction, therefore, provides a seal in which the engagement is at three points which are themselves uniformly and symmetrically disposed with relation to the pouring opening of the container. This insures not only an accurate alinement of the lugs, but since the

fingers of the cap are similarly disposed a 55 corresponding alinement of these fingers, and hence an accuracy of sealing engagement not possible with more than three lugs.

In addition to the foregoing, the seal of the present invention presents certain features of advantage in the formation of the cap fingers themselves, both as to their position about the cap periphery, and as to a bracing or trussing effect which their arrangement exerts upon the stock of the cap. 60 These caps are stamped from sheet metal stock of the proper thickness and resiliency, and where the arrangement of the fingers has not been such as to brace the cap skirt, the cap has been liable to permanently buckle or otherwise distort in use.

In an alternative form a special construction is illustrated in which careful provision is made for inserting the knurl or fluted configuration in the cap rim, which configuration enables the cap to be readily grasped and turned, and which in the ordinary practice of manufacture has the possible effect of buckling the cap rim or injuring the fluting die.

The construction and manner of using my seal, together with a preferred and several alternative embodiments thereof are fully disclosed in the specification which follows, illustrated in the accompanying drawings 85 and particularly pointed out in the appended claims. Throughout specification and drawings like reference characters are correspondingly applied, and in these drawings:

Figure 1 is an elevation of a preferred form of container and closure in accordance with my invention, the closure being shown in section.

Fig. 2 is a plan view of the container.

Fig. 3 is an underneath view of the closure removed.

Fig. 4 is a section of an alternative form of closure, and

Fig. 5 is a view similar to Fig. 1 of a 100 further modification.

I have indicated at 1 a containing vessel which may be of any appropriate size, shape and material. Spaced equidistantly about the mouth of the container and arranged 105 radially with relation to the center of the filling opening thereof are three cam lugs of general pyramidal form. Each lug has

its under face 2 sloped upwardly and outwardly away from the container, its lateral faces 3 sloped upwardly toward each other from opposite ends of the lug, and its top 5 face 4 sloped downwardly toward the under face, all faces terminating at substantially the center of the lug.

The closure of my invention in one embodiment consists of a cap 7 having a continuous depending skirt or flange 8 provided with three similarly formed inturned fingers 9 of relatively large extent. The fingers 9 are disposed at substantially right angles to the cap flange and are arcually 10 curved from their centers outwardly toward their ends, terminating in angularly disposed portions 10 which meet and extend for a short distance as a part of the cap flange forming at these points three fingers 15 or trusses 11 which brace and strengthen the flange against permanent distortion in the seating of the cap.

In the embodiment of Fig. 4 the cap skirt is rolled upwardly and outwardly and back 25 upon itself and extends as a continuous rim 12 which is cut out at three equidistant points 13 to permit it to be passed over the container lugs and be releasably engaged therewith. The cut-outs 13 are of slightly 30 greater size than the lugs to permit the cap to be readily applied to the container.

In the embodiment shown in Fig. 5, the cap skirt is flared downwardly and outwardly as indicated at 14 and terminates in 35 a rolled rim 15 similar to the rim 12. In this form the inner face of the flared portion 14 bears against the lateral faces of the lugs and the terminus of the rim 15 against the under faces of the lugs. The flared 40 formation is especially suitable for receiving the knurl or fluted configuration, presenting as it does a sloped surface to the fluting die and thereby lessening both the liability of buckling the cap skirt in inserting the flutings and injury to the die itself.

The cap 7 is made with its internal diameter greater than the greatest external diameter of the outer portion of the lugs so that the cap is capable of a slight lateral 50 play on the mouth of the container. This lateral play permits of an adjustment of the cap to that plane in which the three lugs lie or in which those bearing surfaces of the three lugs lie which will be engaged by the inturned fingers or rims of the cap.

The adjustment is therefore effected by an automatic lateral shifting of the cap to find a plane of contact with all three lugs which is still parallel with the mouth of 60 the vessel.

The cap in all forms is applied and removed by simple rotation in either direction. In this action the fingers ride along the under faces of the lugs and the flange 65 along one of the pairs of lateral faces of

the lugs reaching its point of maximum engagement at the centers of the lugs.

Various modifications in the form and construction of my invention may obviously be resorted to if within the limits of the 70 appended claims.

What I therefore claim and desire to secure by Letters Patent is:

1. In combination, a container having three cam lugs about its mouth and so arranged with relation to the vertical axis of the container and to each other as to present alined engaging surfaces disposed uniformly in the same horizontal plane, and a closure having a depending skirt terminating in three inturned resilient engaging fingers disposed for progressive engagement by rotation of the closure with said engaging surfaces of the lugs to draw the closure downwardly and inwardly on to the container. 75 80 85

2. In combination, a container having three cam lugs about its mouth and so arranged with relation to the vertical axis of the container and to each other as to present 90 alined engaging surfaces disposed uniformly in the same horizontal plane, and a closure having a depending skirt terminating in three inturned resilient engaging fingers disposed for progressive engagement 95 by rotation of the closure with said engaging surfaces of the lugs to draw the closure downwardly and inwardly on to the container, said fingers at their points of junction with the skirt closure serving as trusses 100 105 for said skirt.

3. In combination, a container having a plurality of spaced cam lugs about its mouth and said lugs having engaging surfaces disposed uniformly in the same horizontal plane, and a closure having an outwardly extended depending resilient skirt terminating in an engaging surface disposed for progressive camming engagement 110 with the engaging surfaces of said lugs to draw the closure downwardly and inwardly on to the container. 115

4. In combination, a containing vessel, three engaging cam lugs symmetrically spaced about the mouth of said vessel, said lugs having upwardly beveled under faces disposed uniformly in the same horizontal plane, and a cap of greater diameter than the maximum diameter of said vessel, and having inturned resilient lug engaging portions adapted to find a horizontal bearing upon the under faces of said lugs to draw the closure downwardly and inwardly on to the container. 120

5. In combination, a container having a 125 plurality of spaced cam lugs about its mouth so arranged with relation to the vertical axis of the container and to each other as to present alined engaging surfaces disposed uniformly in the same horizontal plane, and 130

a closure having a plurality of spaced resilient engaging surfaces disposed for progressive engagement by rotation of the closure in either direction with said engaging surfaces of the lugs.

6. In combination with a container having a series of lugs about its mouth uniformly disposed in the same horizontal plane, each lug of general pyramidal form and consisting of an upwardly sloped under face, opposite lateral faces sloped upwardly toward each other from the ends of the lug, and a downwardly sloped upper face, and all of said faces terminating at substantially the center of the lug, a closure con-

sisting of a rotatable cap having a depending skirt terminating in a series of spaced inturned horizontal lug-engaging portions and said portions arcuately curved from their centers outwardly toward their ends and 20 meeting said cap skirt at their ends and there extending as short trusses adapted to brace the skirt against permanent distortion in the seating of the cap.

In testimony whereof I affix my signature in presence of two witnesses.

JOHN E. DOLDT.
